UNITED STATES PATENT OFFICE

ALVA M. HULL, OF DETROIT, MICHIGAN

BUILDING CONSTRUCTION

Application filed August 30, 1926, Serial No. 132,340. Renewed March 23, 1929.

The present invention relates to building construction and more particularly to methods of and means for constructing buildings quickly and efficiently.

Among the objects of the invention is to simplify the erection of buildings of all sorts and yet produce a structure which is permanent.

Another object is the production of a building structure which shall be fireproof, vermin proof, and resistant to heat transfer through its elements.

Other objects will readily appear to those skilled in the art upon reference to the following description and drawings in which:—

Fig. 1 is a perspective view of one of the wall units;

Fig. 2 is an enlarged view of a portion of the side members of two units secured together;

Fig. 3 shows the several parts of Fig. 2 before securing together and in proper relative position;

Fig. 4 is a view similar to Fig. 2 of a modified form;

Fig. 5 is a view of the same from a different angle;

Fig. 6 is a view similar to Fig. 3 but of the modified form shown in Figs. 4 and 5;

Figs. 7, 8 and 9 are detail views in perspective of certain of the fastening clips;

Fig. 10 is a perspective view of the wall structure with part of the covering removed;

Fig. 11 is a similar view of a corner structure showing a door unit.

As indicated in the drawings a building constructed in accordance with the present invention will have its wall portions made of structural units which need be of very few kinds and each kind, of very few sizes. A blank wall, for example, will be formed of several units such as shown in Fig. 1. A wall with windows will be of the same units with as many window units as desired. A wall with a door will be of the same units with a door unit.

The wall units mentioned are rectangular members of suitable size, composed of two upright stud portions 20, of channel section having a longitudinal rib 21 pressed in the

web thereof, and top and bottom plain channel members 22. These are arranged with their flanges extending inwardly to form the rectangle and are welded as at 23 at all four corners.

When two of the units are placed together it is preferred to secure them together by means of a strip 25, called for convenience the "backbone". This backbone consists of a metal strip having spaced along its edges 60 pairs of tongues 26 of which the two members are bent at right angles to the strip and in opposite directions as shown. The strip will be as wide as a channel member 20 and between the tongues 26 will be provided with 65 spines 27 for a purpose to be described later. When two units are to be secured together, they are placed together with a backbone 25 between and the tongues 26 bent over the flanges as indicated in Fig. 2.

Figs. 4, 5, 6 and 9 show a modification of the backbone which is used when it is desired to leave one side of the wall unfinished. In these figures, a backbone 25^a is shown, that has tongues 26 and spines 27 on only one 75 edge. In this form the tongues 27 are bent over the flanges on one side of the two members 20 and the other side secured by clips 25^b. The latter are preferably perforated as at 25^c (Fig. 9) so that a nail 25^d may be driven 80 in between members 20 to prevent longitudinal displacement of the clip and so that other nails 25^e may be inserted in case it is desired at a later time to finish this side of the wall.

In using the parts mentioned to construct 85 a blank wall, it is preferred to lay on the foundation a channel piece 50 (see Fig. 11) which is slightly wider than the end members 22 of the wall unit and to stand in this a sufficient number of the wall units to make 90 the wall length required. In using standard units, all of the same width, to make a wall length not an even multiple of the unit width, the fractional width may be left at one end or evenly divided between the two ends.

95 Adjacent units are then secured together with the backbone 25 as described and each unit secured in channel 50 by means of a clip 51 of the form shown in Fig. 8. When the units have been thus secured in position 100

a second channel member 52 similar to channel 50 is placed on top and also secured with clips 51.

Corners are formed by the use of corner units such as that shown in Fig. 11. This unit consists of two of the ribbed channel uprights 20 having welded to their webs as at 125 two spined strips 126 and both welded or bolted to adjacent sides of substantially square spacing plates 127. To the free corner of the plates 127 will be welded an angle iron corner piece 128. In this unit, the members 20 will preferably be perforated at the top and bottom of the flanges so that channels 50 and 52 may be secured by bolts 129.

It is preferred to use with the present construction sheet metal joists such as are shown best in Fig. 10. These joists are of I section and composed of two channels spot welded along the middle of the web. Joists of this form permit driving of nails, or equivalents, between the two parts thereof and advantage of that property is taken in the present invention.

Using such joists, as indicated at 60 in Figs. 10 and 11, the wall units and channels 50 and 52 may be and preferably are secured to the joists by means of the clips 61 shown in Fig. 7. These clips are provided with ears 62 long enough to be bent over the channel flanges and with shorter ears 63 adapted to be bent over the low flange 60^a on the joist. The clips 61 are also provided with the central spines 64 adapted to be driven into the joist as indicated at the top of Fig. 10.

When it is desired to provide a wall with a window, use is made of a window unit such as is shown in Fig. 10. This unit consists of two upright ribbed channel members 20 having cross members 70 above and below the window space and within the rectangle thus formed a second rectangle constituting the space formed by other cross members 71 and upright pieces 72. The latter will be welded or bolted to members 71 as indicated at 73. The pieces 71 and 72 will preferably have spines 71^a and 72^a punched out of their flanges and will be unribbed.

Above and below cross pieces 70 the space will preferably be occupied by a short vertical ribbed channel 20^a and short diagonal braces 20^b of the same material. It will of course be obvious that the size of the window space may be varied to accommodate different sizes of windows.

If it is desired to provide the wall with a door, a unit such as is shown in Fig. 11 is shown. In this unit, two upright members 20 are used and these are preferably bolted to channel 50 as indicated at 80, the upper ends having a cross member 22 over which channel 52 is placed and secured by clips 51 and 61. At a point somewhat higher

than the door height, a cross channel 81 is welded to the uprights 20. This channel 81 will be provided with holes 82 in both flanges and at each end as indicated by means of these holes a door frame proper may be bolted thereto, the several holes in each group permitting use of different widths of door frames and some latitude in the location of the frame within the space.

The door frame proper consists of the two upright channel members 83 and a cross member 84 bolted thereto near the top as at 85. As in the case of the window unit, the space above cross member 81 will be occupied with the bracing structure shown and the members 83 and 84 are provided with the punched out spines 27. At the lower ends, the members 83 will be bolted to channel 50 as indicated and the flanges of the latter cut and flattened down as at 86.

When the frame structure has been completed as described, it is first covered with a suitable noninflammable heat insulating sheet 100 by driving down over the spines 27 on the various parts and then over this is placed metal lathing 101 with the spines 27 passing through the meshes thereof. These spines are then bent over to secure the lathing in place and in the bending will pull the lathing taut providing lateral support to channel members 20, thereby bracing the wall units and binding the several parts into a unitary structure. A suitable plastic surfacing material 102 is then applied. Inside surfaces may be and preferably are finished in like fashion.

Building structures produced in the manner and of the means described are practically fireproof as no inflammable material is used and on account of the lack of air circulation in the walls, except in comparatively small bodies of air, and from the walls to and through the floors and ceilings, such structures are very well insulated against passage of heat through the walls. In other words, such structures are warmer in winter and cooler in summer than even the best built wood or brick house built according to conventional practice. Even the studding formed of two uprights 20 does not conduct readily from the one side of the wall to the other on account of the ribs 21 as these not only lengthen the path through which the heat must be carried but form a sort of heat barrier by having a body of air on both sides of the comparatively thin metal. These ribs have also the function of stiffening these uprights and therefore have a double function.

It should also be noted that in the present building construction the several units, while they are fixed together securely, nevertheless under conditions of unequal temperature changes may have sufficient relative movement to prevent any distortion or undue stress in adjacent units or portions thereof. And,

when concrete or other Portland cement compositions are used in conjunction therewith, these, having coefficients of expansion close to or the same as the metal of the units, expand or contract with the latter and therefore do not deteriorate from this cause. Such a structure is therefore "permanent".

Having now described the invention and the preferred form of embodiment thereof, it is to be understood that the said invention is not to be limited to the specific details herein described and illustrated but only by the scope of the claims which follow.

I claim:—

1. In building construction a substantially rectangular wall unit consisting of two side members of channel section having a longitudinal rib in the web thereof and top and bottom channel members, the four members being assembled with their flanges extending inwardly and welded together.

2. Wall construction for building comprising a plurality of previously prepared rectangular units in alignment and having their adjacent sides secured together by means which also provides anchoring means for wall surfacing materials.

3. Wall construction for buildings comprising a plurality of previously prepared rectangular units in alignment and having their adjacent sides secured together, a bottom member and a top member to which all of the units are secured, the means for securing said adjacent sides and for securing said units to the top and bottom members also providing means for anchoring wall surfacing materials.

4. In wall construction for buildings in which a plurality of wall units are used, means for fastening together the adjacent sides of the units and for anchoring surfacing material, said means consisting of a strip of metal having on one of its edges pairs of ears adapted to be bent one over each of the adjacent portions of the units, and also spines adapted to anchor surfacing materials.

5. In wall construction for buildings in which a plurality of wall units are used, means for fastening together the adjacent sides of the units and for anchoring surfacing material, said means consisting of a strip of metal having on both of its edges pairs of ears adapted to be bent one over each of the adjacent portions of the units, and also spines adapted to anchor surfacing materials.

6. Wall construction for building comprising a plurality of previously prepared rectangular units in alignment and having their adjacent sides secured together, said sides forming metal webs extending through said wall from adjacent the inside to adjacent the outside thereof, and means to interfere with the conduction of heat through said wall.
